UNITED STATES PATENT OFFICE.

THOMAS EYNON, OF ROCK ISLAND, ILLINOIS, ASSIGNOR TO WILLIAMS, WHITE & CO., OF MOLINE, ILLINOIS, A CORPORATION OF ILLINOIS.

BOLT-HOPPERING MACHINE.

Application filed September 3, 1921. Serial No. 498,314.

To all whom it may concern:

Be it known that I, THOMAS EYNON, a citizen of the United States, residing at Rock Island, in the county of Rock Island and State of Illinois, have invented certain new and useful Improvements in Bolt-Hoppering Machines; and I do hereby declare the following to be a full, clear, and exact description of the invention, such as will enable others skilled in the art to which it appertains to make and use the same.

This invention relates to mechanism for automatically feeding bolts to a bolt assembling machine, threading machine, or like mechanism for performing one or more operations upon bolts.

The object of the invention is to automatically separate single bolts from a mass, arrange them with similar ends all pointing in one direction and advance them in a stream so that they may be delivered one by one to a mechanism for performing some further operation upon the bolt.

To secure the aforesaid object, the invention consists in the combinations, sub-combinations and details of structure more specifically set forth in the ensuing description, illustrated in the accompanying drawings and defined in the appended claims.

In the accompanying drawings in which like reference characters indicate like parts throughout the several views:

Figure 1 is a side elevation of a machine embodying my invention;

Figure 2 is an end elevation thereof viewed from the right of Figure 1;

Figure 3 is a sectional plan view taken on the line 3-3 of Figure 2, the peripheral groove, track and belt rim being omitted for simplicity of illustration;

Figure 4 is a detail in perspective of one of the bolt separating flights carried on the interior of the bolt separating drum.

In the embodiment of my invention illustrated in the drawings, 43 indicates the base of a framework on which the mechanism is supported. Rising from the base 43 are four heavy standards 44, of equal length arranged in pairs, one pair rearward of the other. Extending crosswise of the base, connecting the standards of each pair, are sills 45. Bearing brackets 3 are arranged on said sills 45, one adjacent each end, each bearing bracket being composed of two

spaced bearing members rising from a flat base. The said bearing members are perforated to receive shafts or axles 32 upon which are mounted cylindrical bearing rollers 22.

Resting upon and adapted to rotate on bearing rollers 22 is a cylindrical drum 1 having annular flanges 2, 2^a extending inward at each end providing a passage entirely through, but of less diameter than the drum. The annular flange 2 on one end of the drum is preferably made of a separate annular plate bolted to the drum, it being shown in Figure 1 at the rear end of the drum. This construction renders the drum capable of being easily bored or otherwise machined. In order to prevent axial movement of the drum it may be provided with an exterior annular groove 22^a in which one pair of rollers 22 engage. The other pair of rollers 22 is shown as engaging a relief surface or track 22^b, the circumference of which is, however, the same as the circumference of the bottom of the groove 22^a. By this arrangement of bearing surfaces on the drum with respect to the bearing rollers the drum may be kept from endwise motion with a minimum of surface frictionally pressing against the rollers.

Supported on a bracket 14 rising from the rearmost sill 45 is a hopper 27 the axis of which is inclined downward toward the drum and which is in form a segment of a cylinder. The inner end of said hopper terminates substantially in the plane of the inner diametrical face of the flange 2, so that material placed in said hopper 27 will slide by gravity and be delivered into the drum between the front and rear flanges.

Within the drum 1 extending substantially from the plane of the inner diametrical face of the flange 2 through the drum and protruding a distance therefrom at the front is a chute 21, V-shaped in cross section, the incline of which may be substantially the same as that of the hopper 27. The said chute 21 is fixed with respect to the hopper 27, the rear end of said chute being supported above and from the hopper 27 by braces or brackets 28. That portion of the chute 21 that projects through the front end of the hopper is sustained by brackets 12 and 13 which are secured to the front side of the front sill 45 and incline upward and inward into contact with the sides of the chute 21 which may be secured to the upper ends 110

of said brackets. An open-ended, parallel-sided slot 21^a is formed in the projecting end of the chute.

Arranged in a plurality of circumferential rows about the inner periphery of the drum are individual bolt separating devices in the nature of flights, 41, said flights in any one row being equally spaced apart and in location staggered with respect to the flights in an adjacent row. In the apparatus shown there are two circumferential rows of bolt flights 41, bolted to the inner surface of the drum, each row having eight of such devices equally spaced circumferentially. 10 One edge of each flight 41 is provided with a groove 42 which may be substantially of a size to receive one of the bolts being fed. The flights are secured to the drum in such a position that the groove 42 extends parallel with the axis of rotation of the drum and the groove is placed on that side of the flight which advances during rotation of the drum.

A pair of brackets 7 is secured to the front 25 of the forward sill 45, one on each side of a perpendicular plane including the axis of the drum. Extending between the upper ends of said brackets 7 is a rock shaft 33 supporting double bearing members 9 which 30 are adapted to oscillate on or with shaft 33 and to be adjusted thereon toward or from each other. The upper ends of said members 9 are pierced at right angles to the shaft 33 and receive the rear end trunnions of a 35 pair of rolls 31. The front ends of said rolls 31 are journaled in bearings 10, adjustable by means of pins 10^a in the arcuate slots 10^b in the arms 24 which project upward from rigid bracket arms 23 stretching 40 diagonally upward and inward from the brackets 7 secured to the front side of the forward sill 45. A spreader 29 connects the upper ends of the arms 24 together. From the construction described it will be apparent 45 that the inclination of the rolls 31 may be changed and also that the distance apart of the inner ends of said rolls may be varied. The discharge ends of rolls 31 may be separated more or less by substituting spacing 50 bars 29 of suitable length, or by making the connections between spacing bar and bearings 10 adjustable (not shown) in any obvious manner. Should the adjustment of the rear ends of said rolls render it necessary 55 the driving gears 20, by means of which one roll may be driven from the other, may be removed and gears of a different size substituted. The rearmost end of the trunnion of one of the rolls 31 (the right hand roll 60 as illustrated, looking toward the front end of the machine) is provided with a grooved pulley wheel 19 by which the said right hand roll may be rotated and, by engagement of the gears 20, both rolls rotated in opposite 65 directions, the direction of rotation being

such that their adjacent surfaces move upward in unison.

In order to operate the mechanism thus far described, the transmission gearing shown in the drawings may be used, although other suitable transmission, it will be clear, can be substituted for it without changing the principles of my invention. A main driving pulley 17 may receive motion from a line shaft or from any desired prime 70 mover. The main driving pulley 17 is banded by belt 17^a to a pulley 16 which rotates about the axis of the stud or shaft 36 carried by the hanger 6 secured to the under side of the rear sill 45. Rotating with the pulley 16 is a cone or stepped pulley 8 held from endwise movement on the shaft 36 by the collar 26. Carried on a stud or shaft 35 projecting from the bearing hanger 5, supported on the upper side of the base 43 85 in substantially the same plane as the hanger 6, is a cone or stepped pulley 8^a having its graduated band surfaces reversed in position with respect to those of pulley 8, so that a belt passed around the largest step of the pulley 8 will fit around the smallest step of the pulley 8^a. The cone pulley 8^a is prevented from slipping endwise on shaft 35 by means of the collar 25. A suitable driving belt 8^b is adapted to drive the cone pulley 8^a from said cone pulley 8. A gear wheel 37 is rigidly secured with respect to the cone pulley 8^a so as to rotate with it. Said gear 37 is in mesh with a larger gear 15 mounted on a rotary shaft 34 which is journaled in 100 bearing brackets 4 secured to the inner side faces of the left hand standards 44. Rotation of the gear 15 turns shaft 34. On said shaft 34, between the bearing brackets 4, is a belt pulley 11, around which and around 105 the exterior periphery of the drum 1 is engaged a belt 11^a whereby rotation of the pulley 11 rotates the drum 1. For convenience a raised belt rim 11^b may be formed on or secured to the drum 1, which belt rim 110 may be crowned if desired. Secured to the forward end of the shaft 34 is a grooved pulley 18 designed to receive a belt for driving the pulley 19, before mentioned, on the rear end of the trunnion of left-hand feed 115 roller 31.

By the transmission mechanism described it will be evident that gear 15 may be rotated at various speeds by properly adjusting the belt 8^b with respect to the driving and driven cone pulleys 8 and 8^a, respectively. The gear 15 imparts rotation to the shaft 34 from which the drum and the feed rolls 31 are driven so that the said drum and feed rolls may be operated at various speeds 125 as may be found desirable.

Threaded through suitable bearings 38 in the corners of the base 43 are adjusting screws 30 having at their lower ends bearing shoes 39 adapted to thrust upon the 130

foundation on which the machine is to be placed; said screws 30 having hand wheels 40 at their upper ends by means of which they may be rotated. The mechanism 5 described may therefore be adjusted for different machines and may be suitably leveled to suit conditions.

In operation headed bolts will be shoveled or otherwise thrown indiscriminately into the hopper 27. Gravity will cause said bolts to slide downward and be discharged into the interior of the drum 1 between the annular flanges 2 and 2^a. In the machine shown the drum is designed to rotate in a clockwise direction viewed from the rear. As the drum rotates the bolts will be tumbled about in the bottom of the drum and when any bolt happens to fall lengthwise into a pocket 42 it will be carried upward and dropped sideways into the chute 21. The flight and pocket are so designed that only one bolt may be picked up by one flight at one time. The dropped bolt will slide sideways down into the angle formed by the sides of the chute 21, be held in a longitudinal position and move endwise down the chute until the notch 21^a is reached, whereupon the point of the bolt will fall through said notch, the head being momentarily detained by the walls thereof and the bolt will pass thence into the space between the rolls 31, point downward, being sustained by its head on the rolls with its end extending downward. Thus a row of bolts will accumulate between the rolls 31 and the motion of said rolls combined with their inclination will effect the advance of the bolts from end to end thereof. The bolts may be discharged from the ends of the rolls 31 between the spaced bearings 10, the heads passing underneath the spacing bar 29. If desired a predetermined number of bolts may be accumulated on the rollers 31 until the mechanism to which the bolts to be delivered is ready 45 to receive a charge or load of bolts. The entire series accumulated on the rolls 31 may then be pushed along said rolls and delivered to the runway or other receiving means of a bolt and nut assembling or finishing machine.

What I claim and desire to secure by Letters Patent is:

1. In mechanism of the class described,

a rotary drum adapted to receive bolts in its interior, a bolt separating flight on the 55 inner surface of said drum said flight having a groove of such dimensions as to adapt it to carry but one bolt at a time, and a chute extending into said drum for receiving bolts dropped from the flight. 60

2. In mechanism of the class described, a rotary drum adapted to receive bolts in its interior, said drum having a plurality of flights spaced apart on the inner surface thereof, each flight having a groove of such 65 dimensions as adapt it to carry but one bolt at a time, and a chute extending into said drum for receiving bolts dropped from the flights.

3. In mechanism of the class described, 70 a rotary drum adapted to receive bolts in its interior, said drum having a plurality of rows of bolt separating flights on the inner surface thereof, the flights of one row being in staggered relation with respect to the flights of the other row, and a chute extending into said drum for receiving bolts dropped from the flights. 75

4. In mechanism of the class described, a rotary drum adapted to receive bolts, a 80 bolt separating flight on the inner surface thereof having a groove of such dimensions as to carry but one bolt at a time in a position parallel with the axis of the drum, a chute, V-shaped in cross section, extending 85 into said drum adapted to receive bolts discharged sidewise from said flight.

5. In mechanism of the class described, a frame, a pair of parallel spaced rolls, spaced brackets on the frame adjacent one 90 end of the rolls, a pin extending between said brackets, rockable bearing members on the pin, said bearing members being adjustable lengthwise of the pin, bearing orifices in said rockable bearing members at right 95 angles to the pin for receiving the ends of said rolls, and vertically adjustable bearings for the other ends of the rolls.

6. In mechanism of the class described, a frame, cylindrical bearings thereon, a 100 drum having an annular groove adapted to fit one pair of said bearings, and a relief cylindrical surface resting upon another pair of bearings.

In testimony whereof I affix my signature.

THOMAS EYNON.
